UNITED STATES PATENT OFFICE.

BRUNO KNIFFLER, OF STONEHAM, MASSACHUSETTS.

PROCESS OF DISSOLVING SIZE FOR PAPER-MAKING.

No. 816,865.

Specification of Letters Patent.

Patented April 3, 1906.

Application filed July 7, 1905. Serial No. 268,710.

To all whom it may concern:

Be it known that I, BRUNO KNIFFLER, of Stoneham, county of Middlesex, State of Massachusetts, have invented an Improvement 5 in Processes of Dissolving Size for Paper-Making, of which the following description, in connection with the accompanying drawing, is a specification, like characters on the drawing representing like parts.

This invention relates to a process of dissolving size for paper-making, and has for its object to improve the process to the end that a more perfect emulsion is produced with a size containing a larger percentage of free or 15 unsaponified resin than the ordinary or commercial resin soap, such size being herein designated "resin size."

The drawing shows in vertical section one 20 form of apparatus by which my improved process may be carried out.

In carrying out my invention a measured volume of resin size is heated, and small jets or streams of the liquefied size are then subjected to the action of forcibly-expelled jets or streams of hot water in predetermined 25 relative proportions, which act to disintegrate the jets or streams of liquefied size and produce an emulsion. A measured or predetermined volume of cold water is then 30 added to the emulsion thus produced for the purpose of diluting it to the required strength.

While it is obvious that many ways may be provided for carrying out this invention, one way is herein shown for the sake of illustration.

a represents a tank adapted to contain a measured volume of resin size. A pipe a' leads from the bottom of the tank a to a heating apparatus, which conducts the size there- 35 to in order that it may be heated, and said pipe contains a valve for regulating the flow. The heating apparatus consists, essentially, of a drum a², containing vertical tubes a³, which are connected at their upper and lower 40 ends to the steam-chambers a⁴ a⁵, which are respectively connected with the steam-pipes a⁶ a⁷. The size flows into the drum a² around the steam-tubes and becomes heated. A pipe b leads from the lower end of the drum 45 a² to a receiver b', which is closed at its upper end b² by a cap, through which a rod b³ passes and which is enlarged at its lower end portion and provided with a perforated end piece or plate b⁴. The rod b³ extends down through 50 the receiver b' and has at its lower end a plate b⁵, from the under side of which several pins

b⁶ project, which are adapted to be thrust into the perforations in the plate b⁴ when the rod b³ is pressed down. The pins are provided for the purpose of closing the perforations or for clearing the perforations in case they should become clogged. The liquefied size flows from the heating-drum a² to the receiver b' and passes through the perforations in the plate b⁴ by gravity. The perforations 60 are quite small, so that the liquefied size will be discharged in very small jets or streams. The lower end portion of the receiver b' is contained in an emulsifying-chamber.

c represents an upright tube open at both 70 ends which is connected to a pipe c' at a point substantially midway its length, and concentrically arranged within said tube c is a tube c² of lesser diameter, which is formed with perforations from end to end and which 75 is attached at each end to the tube c. The inner perforated tube is made substantially as long as the outer tube c, and the means employed for connecting it with said outer tube closes the space between the two tubes 80 at the ends to thereby form an annular space or chamber between the two tubes, the exits therefrom being the perforations in the inner tube c². The space within the inner tube c² serves as the emulsifying-chamber, and the 85 lower end of the receiver b' extends down into said chamber for a short distance, being located at the upper end of the chamber. The pipe c' has connected with it a cold-water pipe c³ and a steam-pipe c⁴, and the steam enters and passes by the end of the cold-water pipe c³ and meets the water which enters the pipe c', so that the water is heated and is forced by the steam-pressure into the annular space or chamber surrounding the emul- 90 sifying-chamber and is caused to enter the said emulsifying-chamber through the perforations in the tube c². The perforations in the inner tube are quite small, so that the hot water issues in small jets or streams, and 95 said perforations being located in the side wall of the emulsifying-chamber said jets or streams will be directed at right angles or thereabout to the jets or streams of liquefied size discharging from the receiver b', and as a 100 result the small jets or streams of liquefied size are disintegrated and becoming mixed with the hot water produce an emulsion which is discharged from the lower end of the emulsifying-chamber. The emulsifying- 105 chamber is contained in an empty tank d, so 110 that the emulsion is discharged into said

tank. The volume of hot water used will be regulated by a valve, so that a predetermined proportion of hot water will be used relative to the volume of size and an emulsion of predetermined relative proportions thus produced. The emulsion rises in the tank *d* until it reaches a level near the top of the emulsifying-chamber, at which point an outlet-pipe *d'* leads from the tank to conduct the emulsion to another tank *e*, which is many times larger than the tank *d* and contains a measured volume of cold water. The emulsion flows freely from the tank *d* to the tank *e*. The inlet end of the outlet-pipe *d'* 15 may be screened, if desired. By placing the emulsifying-chamber in the tank *d* the emulsion contained in said tank will be more or less agitated by the steam-pressure; but in practice the emulsifying-chamber may be located above the tank *d*, if desired. I prefer, however, to agitate the emulsion in the tank *d*, and hence extend the steam-pipe *a'* down into said tank.

In carrying out my invention the relative proportions of the emulsion contained in the tank *d* will be fifteen of hot water to one of size, or thereabout and in the tank *e* thirty of water to one of size or thereabout; but these relative proportions may be widely varied.

This process is particularly designed to be carried on on a large scale and to produce a

more perfect emulsion. Even though using a size which contains a very large percentage of free or unsaponified resin by subjecting the small jets or streams of liquefied size to the action of the forcibly-expelled jets or streams of hot water the jets or streams of size are so completely disintegrated that any free resin therein will be emulsified or held in suspension, and therefore will act advantageously instead of injuriously when introduced into the paper-pulp.

Having thus described my invention, what I claim as new, and desire to secure by Letters Patent, is—

The process herein described of preparing size for paper-making, which consists in heating a measured volume of resin size, then subjecting the same in small jets or streams to the action of forcibly-expelled jets or streams of hot water, in predetermined relative proportions, to disintegrate the jets or streams of liquefied size and produce an emulsion, and in then adding the emulsion to a measured volume of cold water.

In testimony whereof I have signed my name to this specification in the presence of two subscribing witnesses.

BRUNO KNIFFLER.
